UNITED STATES PATENT OFFICE.

HIRAM C. UNDERWOOD, OF METUCHEN, NEW JERSEY.

DESIGN FOR A COIN-MAT.

SPECIFICATION forming part of Design No. 32,525, dated April 17, 1900.

Application filed March 8, 1900. Serial No. 7,934. Term of patent 14 years.

To all whom it may concern:

Be it known that I, HIRAM C. UNDERWOOD, a citizen of the United States, and a resident of Metuchen, in the county of Middlesex and State of New Jersey, have invented and produced a new and original Design for a Coin-Mat, of which the following is a full, clear, and exact description.

Reference is to be had to the accompanying drawings, forming a part of this specification, in which similar characters of reference indicate corresponding parts in both views.

Figure 1 is a perspective view of a coin-mat, showing my design; and Fig. 2 is a transverse section of the same on the line 2 2 in Fig. 1.

The invention relates to coin-receivers, coin-trays, and coin-tablets arranged to support loose coin for conveniently picking it up with gloved or ungloved fingers.

The design in its entirety consists of spher-

ical depressions A, surrounded by a plurality of spherical rises B, saddles or ridges C connecting adjacent rises and depressions with each other, drain-openings D appearing in the bottoms of the depressions.

The leading feature of the design consists of the depressions, the rises, and the saddles.

Having thus fully described my invention, I claim as new and desire to secure by Letters Patent—

The design for a coin-mat, as herein shown and described.

In testimony whereof I have signed my name to this specification in the presence of two subscribing witnesses.

HIRAM C. UNDERWOOD.

Witnesses:

THEO. G. HOSTER,
EVERARD BOLTON MARSHALL.
